POTENTIOMETER WINDING DEVICE

Asa C. Goddard, Mentor, Ohio, assignor, by mesne assignments, to Jack & Heintz Precision Industries, Inc., Cleveland, Ohio, a corporation of Delaware

Application March 30, 1945, Serial No. 585,726

9 Claims. (Cl. 242—4)

1

This invention relates to automatic winding machines and has for one of its primary objects to provide an improved machine for the wire winding of electrical devices.

A more specific object is to provide such a machine by which circular objects may be wire wound which involves the use of a wire feed holder and a split driven gear to carry the same and to provide a variable speed friction drive for the work turn table such drive to include a manually adjustable speed adjustment device and a spring operated friction drive between the manual adjustment device and the work holding table to prevent binding of parts and breakage of the wire, or thread, and to insure its even feed and close spaceless and non-overlapping winding onto the work.

With the foregoing and other objects in view the invention resides in the combination of parts and in the details of construction hereinafter set forth in the following specification and appended claims, certain embodiments thereof being illustrated in the accompanying drawings, in which:

Figure 1 is a view partly in side elevation and partly in longitudinal section taken through the winding machine;

Figure 2 is a view partly in top plan and partly in cross section of the machine;

Figure 3 is a view in section taken along line 3—3 of Figure 2;

Figure 4 is a view in elevation of the manual adjustment means for the variable speed drive for adjusting the speed of rotation of the work holding turntable;

Figure 5 is a view in section taken along line 5—5 of Figure 1 showing the wire feed holder, the work, the wire feeding spool and the split driving gear.

Referring more particularly to the drawings, shaft 1 is driven by some suitable electric motor and carries a driving gear 2 that meshes with gear 3 carried by a shaft 4 and a gear 5 carried by a shaft 6. Shaft 6 carries a worm 7 meshing with a gear 8 that is fixed by a pin 11 to a stub shaft 9 mounted for rotation in suitable bearings 12 and 13 in the housing 10. Fast with shaft 9 by means of a pin 14 is one wheel 15 of a variable speed drive. The other wheel 16 is loosely mounted on shaft 9 for alignment purposes. Wheel 16 is also mounted on a shaft 17 for rotation in housing bearing 18. Wheel 16 is slidably mounted on shaft 17 and provided with a longitudinal slot 19 to receive a shaft pin 20 to prevent relative rotation between the shaft 55 with a side slot to receive a retaining track 53

and wheel. Shaft 17 also has a collar 21 pinned at 22 thereto. A compression coil spring 23 surrounds shaft 17 and is interposed between collar 21 and wheel 16. Between the two opposed concave surfaces of wheels 15 and 16 is interposed a friction disc 24 with a replaceable peripheral member 25 of rubber or like material. Disc 24 is pinned at 26 to a shaft 27 which is connected at 65 to a bracket 66 provided with an arcuate slot 28 to receive a clamping bolt 29 which is screw-threaded into the casing and provided with a washer 30. By this arrangement the bracket 66 may be adjusted to the neutral position shown in Figure 4 to bring the disc 24 to the position shown in Figure 2 to effect a 1 to 1 ratio friction drive from wheel 15 to wheel 16. An adjustment of the bracket to the right or left in slot 28 varies the relationship between disc 24 and the two wheels 15 and 16 to correspondingly adjust the friction drive ratio.

Shaft 17 carries a worm gear 31 that meshes with a gear 32 carried by a stub shaft 33 rotatably mounted in a housing bearing 34. A friction disc 35 is pinned at 36 to gear 32. Loosely mounted on shaft 33 and resting on friction disc 35 is a collar 37. Shaft 33 has a portion 38 of angular cross section to receive a disc 39 to be rotated thereby. The upper extremity 40 of shaft 33 is screw-threaded to receive a nut 41 and interposed between this nut and disc 39 is a compression coil spring 42. To disc 39 are removably secured a plurality of vertical supports 43 each of which has secured to its upper extremity an arcuate plate 44 with a pair of spaced pins 45. These pins constitute the work supporting elements, the work in the illustration being a ring 46 which is to be wound with fine wire. The ring 46 is provided with round recesses to receive pins 45. Retaining leaf spring clips 47 may be sprung under collar 37 and over the top of ring 46 to retain the ring in place for the wire winding operation.

Thus it will be seen that the speed of rotation of wheel 16 by wheel 15 is dependent upon the adjustment of disc 24 and that the speed of rotation of the work supporting disc 39 is further dependent upon the adjustment of nut 41 and the compression of spring 42 and the resulting frictional drive adjustment between gear 32 and disc 39 through collar 37 and friction disc 35.

The housing 10 has a cut-away portion between points 50 and 51. A split gear 52 is provided to have a split substantially equal to the space between points 50 and 51. Gear 52 is provided with a side slot to receive a retaining track 53

integral with housing 10. This gear 52 is engaged by gears 3 and 5 to be driven thereby as gears 3 and 5 are driven by the motor driven gear 2. Figure 5 shows gear 52 to be in mesh with gear 5, due to the fact that Figure 5 is a section taken along line 5-5 of Figure 1. It will be appreciated that due to the fact that gear 52 is split there are certain periods in its rotation when the split portion will become opposite gear 3 and gear 5 but at least one of these gears 3 and 5 will always be in mesh with gear 52 and both of them will be in mesh with gear 52 during the major portion of each rotation of the latter.

The interior surface of gear 52 has secured thereto a wire feed holder 54 provided with a cross pin 55 to rotatably receive a guide wheel 56 which is centered against the holder by a compression coil spring 57 whose compression is adjustable by a nut 58 screw-threaded to pin 55. To holder 54 is connected at 60 a wire tension control leaf spring 61. A cross pin 62 in the holder 54 removably receives a spool 63. The spring 61 is preferably bent to increase the tension on spool 63. There is no danger of breakage of the wire from too tight an adjustment of nut 58 as if wheel 56 becomes bound the wire will slip around the wheel.

After the ring 46 is clamped into place for winding, one end of the wire 64 on spool 63 is brought forward from the spool, as viewed in Figure 1, to the right and under and counter-clockwise about and over the top of guide wheel 56 and thence under ring 46 and secured thereto. The direction of rotation of gear 2 is counter-clockwise to rotate gears 3 and 5 clockwise which mesh with gear 52 to drive the latter counter-clockwise. The split gap of the casing and gear 52 between points 50 and 51 permits insertion of ring 46 therebetween to be held onto and be rotated by the turn table. Gear 52 as it rotates carries the holder 54, the guide wheel and spool in a counterclockwise direction about the rim of ring 46 that has been rotated counterclockwise to an extent equal to the diameter of a strand of wire for each rotation of the holder. This brings about a wrapping of wire 64 in a counterclockwise direction about the rim of ring 46 in a continuous contiguous single layer winding.

By means of the adjustable bracket 66 and the adjusting nut 41 the rate of rotary movement of ring 46 may be so correlated with the speed of rotation of gear 52 with the spool 56 and wire wound feed spool 63 and tension control spring 61 that there will be no overlapping of wire and that there will be virtually no space between each turn of wire on the ring. The motor for driving shaft 1 may obviously be started or stopped by any suitable means. The resiliency of the frictional driving means above described provides a safety factor in case of binding. The adjustable variable speed drives including the wheels 15 and 16 and disc 24 as well as that between the turntable and gear 32 moreover make it possible to accommodate various types of windings with respect to sizes of wires and rings and the spacing of wire windings.

I claim:

1. In a motor driven machine for winding wire about the rim of a ring, a rotatable turntable for supporting said ring, an annular split gear disposed at right angles to and encompassing a portion of said ring and having secured thereto a wire feed holder including a wire feeding spool and a guide wheel in spaced relationship on oppo-

site sides of said portion, a motor driven gear train for rotating said turntable and for rotating said split gear and wire carrying holder about the rotating ring rim to wind the wire thereabout in a single continuous contiguous winding, said gear train including a gear in driving relationship with said turntable and manually adjustable friction drive means between said turntable and said turntable gear for varying the speed ratio drive therebetween.

2. In a motor driven machine for winding wire about the rim of a ring, a rotatable turntable for supporting said ring, an annular split gear disposed at right angles to and encompassing a portion of said ring and having secured thereto a wire feed holder including a wire feeding spool and a guide wheel in spaced relationship on opposite sides of said portion, a motor driven gear train for rotating said turntable and for rotating said split gear and wire carrying holder about the rotating ring rim to wind the wire thereabout in a single continuous contiguous winding, said gear train including a pair of motor driven gears disposed in such meshing relationship with said split gear that as the split portion of said split gear is rotated adjacent one of said motor driven gears the other of said motor driven gears is still in mesh with said split gear to drive the latter.

3. In a motor driven machine for winding wire about the rim of a ring, a rotatable turntable for supporting said ring, an annular split gear disposed at right angles to and encompassing a portion of said ring and having secured thereto a wire feed holder including a wire feeding spool and a guide wheel in spaced relationship on opposite sides of said portion, a motor driven gear train for rotating said turntable and for rotating said split gear and wire carrying holder about the rotating ring rim to wind the wire thereabout in a single continuous contiguous winding, said gear train including a gear in driving relationship with said turntable and manually adjustable friction drive means between said turntable and said turntable gear for varying the speed ratio drive therebetween, said gear train also including a pair of motor driven gears disposed in such meshing relationship with said split gear that as the split portion of said split gear is rotated adjacent one of said motor driven gears the other of said motor driven gears is still in mesh with said split gear to drive the latter.

4. In a motor driven machine for winding wire about the rim of a ring, a rotatable turntable for supporting said ring, an annular split gear disposed at right angles to and encompassing a portion of said ring and having secured thereto a wire feed holder including a wire feeding spool and a guide wheel in spaced relationship on opposite sides of said portion, a motor driven gear train for rotating said turntable and for rotating said split gear and wire carrying holder about the rotating ring rim to wind the wire thereabout in a single continuous contiguous winding, said gear train including a motor driven gear, a gear in driving relationship with said turntable and an adjustable variable speed friction driven mechanism between said motor driven gear and said turntable gear.

5. In a motor driven machine for winding wire about the rim of a ring, a rotatable turntable for supporting said ring, an annular split gear disposed at right angles to and encompassing a portion of said ring and having secured thereto a wire feed holder including a wire feeding spool

and a guide wheel in spaced relationship on opposite sides of said portion, a motor driven gear train for rotating said turntable and for rotating said split gear and wire carrying holder about the rotating ring rim to wind the wire thereabout in a single continuous contiguous winding, said gear train including a motor driven gear, a gear in driving relationship with said turntable and an adjustable variable speed friction drive mechanism between said motor driven gear and said turntable gear, said variable speed drive including a wheel driven by said motor driven gear and a wheel in driving relationship with said turntable gear and a disc therebetween and in frictional engagement with both, and manual means for adjusting the angular relationship of said disc with said wheels for varying the speed ratio between the driving and driven wheel.

6. In a motor driven machine for winding wire about the rim of a ring, a rotatable turntable for supporting said ring, an annular split gear disposed at right angles to and encompassing a portion of said ring and having secured thereto a wire feed holder including a wire feeding spool and a guide wheel in spaced relationship on opposite sides of said portion, a motor driven gear train for rotating said turntable and for rotating said split gear and wire carrying holder about the rotating ring rim to wind the wire thereabout in a single continuous contiguous winding, said gear train including a pair of motor driven gears disposed in such meshing relationship with said split gear that as the split portion of said split gear is rotated adjacent one of said motor driven gears the other of said motor driven gears is still in mesh with said split gear to drive the latter, one of said motor driven gears being in driving relationship with said turntable and an adjustable variable speed friction drive mechanism between said motor driven gear and said turntable gear.

7. In a motor driven machine for winding wire about the rim of a ring, a rotatable turntable for supporting said ring, an annular split gear disposed at right angles to and encompassing a portion of said ring and having secured thereto a wire feed holder including a wire feeding spool and a guide wheel in spaced relationship on opposite sides of said portion, a motor driven gear train for rotating said turntable and for rotating said split gear and wire carrying holder about the rotating ring rim to wind the wire thereabout in a single continuous contiguous winding, a gear in driving relationship with said turntable and manually adjustable friction drive means between said turntable and said turntable gear for varying the speed ratio drive therebetween, a motor driven gear, and a manually adjustable variable speed friction drive mechanism between said motor driven gear and said turntable gear.

8. In a motor driven machine for winding wire about the rim of a ring, a rotatable turntable for supporting said ring, an annular split gear disposed at right angles to and encompassing a portion of said ring and having secured thereto a wire feed holder including a wire feeding spool and a guide wheel in spaced relationship on opposite sides of said portion, a motor driven gear train for rotating said turntable and for rotating

said split gear and wire carrying holder about the rotating ring rim to wind the wire thereabout in a single continuous contiguous winding, said gear train including a pair of motor driven gears disposed in such meshing relationship with said split gear that as the split portion of said split gear is rotated adjacent one of said motor driven gears the other of said motor driven gears is still in mesh with said split gear to drive the latter, one of said motor driven gears being in driving relationship with said turntable and an adjustable variable speed friction drive mechanism between said motor driven gear and said turntable gear, said variable speed drive including a wheel driven by said motor driven gear and a wheel in driving relationship with said turntable gear and a disc therebetween and in frictional engagement with both, and manual means for adjusting the angular relationship of said disc with said wheels for varying the speed ratio between the driving and driven wheel.

9. In a motor driven machine for winding wire about the rim of a ring, a rotatable turntable for supporting said ring, an annular split gear disposed at right angles to and encompassing a portion of said ring and having secured thereto a wire feed holder including a wire feeding spool and a guide wheel in spaced relationship on opposite sides of said portion, a motor driven gear train for rotating said turntable and for rotating said split gear and wire carrying holder about the rotating ring rim to wind the wire thereabout in a single continuous contiguous winding, a gear in driving relationship with said turntable and manually adjustable friction drive means between said turntable and said turntable gear for varying the speed ratio drive therebetween, a motor driven gear, and a manually adjustable variable speed friction drive mechanism between said motor driven gear and said turntable gear, a motor driven gear, a gear in driving relationship with said turntable and an adjustable variable speed friction drive mechanism between said motor driven gear and said turntable gear, said variable speed drive including a wheel driven by said motor driven gear and a wheel in driving relationship with said turntable gear and a disc therebetween and in frictional engagement with both, and manual means for adjusting the angular relationship of said disc with said wheels for varying the speed ratio between the driving and driven wheel.
